PUMP DISPENSER

Thomas L. Titus, Cheyenne, Wyo., assignor to
Wyott Manufacturing Co. Inc., a corporation
of Wyoming

Application April 15, 1950, Serial No. 156,190

8 Claims. (Cl. 222—378)

1

This invention relates to pump dispensers, and in the preferred embodiment, here illustrated, to such dispensers used for dispensing such food and beverage liquids as melted butter, soda fountain syrups, and the like, having a certain amount of viscosity.

It is a primary object of this invention to provide a pump dispenser of the fewest possible parts and of economical construction, without sacrificing efficiency of operation, and permitting disassembly for complete cleaning.

Another principal object of this invention is to provide such a pump dispenser having the conventional plunger and discharge tube members formed as one novel vertically operable pipe-like member.

Another object is to provide a novel simplified piston and floating cylinder construction in cooperation with such novel single plunger and discharge tube member.

Another object is to provide such a novel pump dispenser with the floating cylinder having a lower intake port adapted to be closed by a gravity resting thereof upon the floor of the liquid container.

Other and further objects will be apparent from the following detailed description, and by reference to the drawings in which:

Figure 1 is a vertical cross-sectional view of my novel pump dispenser, shown in inoperative condition ready for use;

Figure 2 is a partial vertical cross-sectional view thereof, showing the relationship of parts upon commencement of plunger downstroke operation;

Figure 3 is a view similar to Figure 2, but illustrates the relationship of parts at the moment of return to uppermost plunger position after a full downstroke;

Figure 4 is a horizontal cross-sectional view of the plunger-tube, piston and floating cylinder, taken on the line 4—4 of Figure 1;

Figure 5 is a horizontal cross-sectional view of the upper portion of the pump, taken on the line 5—5 of Figure 1, showing the plunger-tube, check valve, adjustable stop regulator post, spring clip catch, and regulator plate; and

Figure 6 is a plan view of the outer portion of the spout, showing the removable head and spring yoke catch.

Throughout the various views of the drawings the same reference characters have been used to represent like parts.

Referring to the drawings, in Figure 1 I have illustrated my pump dispenser as it is sometimes used, namely, with the inner vessel 1, having the liquid to be dispensed therein, placed in an outer vessel 3. In actual use, depending upon the liquid to be dispensed, there are times when a refrigerant

2

such as ice is placed in the outer vessel 3, and then there are times when a heater element will be used in a different design outer vessel 3 to keep the liquid to be dispensed within the inner vessel 1 in liquid state. It is to be understood that the outer vessel 3 forms no part of this invention, merely being illustrated for completeness of the view. My invention comprises a novel pump, indicated generally as P, extending through the removable cover 2 of the container 1, and having the pump floating cylinder 45 resting on the floor of that container 1.

This invention is an improvement over my United States Patent No. 2,408,009, and pending application Serial No. 30,045.

A tubular guide sleeve 4 is silver soldered through an opening in the cover 2, provided for the purpose, and rigidly to the cover, as illustrated. A regulator post 28 is soldered to the upper side of the cover, positioned with relation to the guide 4 as illustrated. A pipe-like plunger tube 8, having an external diameter adapted to fit snugly and slidably through guide member 4, is provided to extend well on both sides of guide 25 4, and the lower end 41 thereof is slightly reduced in diameter for reason to be explained. An extension 9, similar to 8 but of larger diameter so as to snugly overlap tube 8, is silver soldered to the upper open end of 8 and extends 8 upwardly 30 a small distance. The top edge of tube 8, within tube extension 9, forms a valve seat for gravity-operable ball-check valve 10. An annular shoulder is formed on the lower outer periphery of tube portion 9, adapted to provide a seat against which 35 a stop regulator plate 27 abuts. Stop or regulator plate 27, of dog-leg design for purpose of using a short regulator post 28 in association therewith, has its plunger side portion made with an opening to fit over the lower reduced periphery of member 9 and then the two are welded together so that plate 27 projects at a right angle from and as a rigid part of the tube 8—9. An opening is provided in the outer end of plate 27 and a suitable guide collar 40 is secured to that 40 opening. The collar 40 has its inside diameter adapted to fit snugly and yet slidably over the exterior of the post 28. Collar 40 is a rigid part of plate 27, and is adapted for sliding movement along said post, as will be explained. A pair of telescopedically associated spring-cage sleeves, 5 and 6, are provided, as illustrated, to extend between the under side of plate 27 and the top of the cover 2, in spaced relation around the plunger-tube 8—9. A suitable outwardly expanding coil tension spring 7 is placed around the tube 8—9 and within and between opposing inwardly extending horizontal end portions of cage sleeves 5 and 6, so as to normally exert an upward pres-

sure against the plate 27. A plurality of spaced apart annular grooves 29 is provided on the periphery of post 28, adapted to receive a tensioned snap-wire-clip 30 removably in any one of those grooves. Said clip 30 is designed to exert a sufficient inward tension pressure, when snapped in place in alignment with a groove 29, as illustrated, to hold the plunger-tube 8-9, by its plate 27, against the tension of the coil spring 7, as will be further explained. The upper portion 9, of the plunger-tube 8-9, is externally threaded, and a suitable screw cap 25 is removably screw-threaded thereover, seating a gasket 26 for closing that end of the tube. A spout 20 is provided for extending an opening in the side of the tube opposite from the post 28 and a spaced distance below the top of the tube-plunger, whereby the latter distance provides a fluid channel offset for receiving the ball check upon discharge operation, as illustrated in Figure 2. A removable spout head, 21, of suitable design as constructed and illustrated, is provided in the outer end of the spout, being tensionally held therein and against a washer gasket 22 by means of a yoke tensioned snap 24. Yoke 24 is pivoted at 31, and formed as illustrated to exert an inward spring pressure on the spout head 21 when snapped into a transverse groove 32 provided in the head. A discharge port 23 is provided in the lower outer extremity of the head 21. The inner diameter of spout 20 is less than the diameter of the ball check 10. Upper spring cage member 6 has its lower periphery flared at 6a, which acts to engage the cover 2 upon a downward movement of the plunger-tube, thus limiting the extent of movement thereof in that direction. The distance between the under side of flange 6a and the top of cover 2 defines the length of downward plunger stroke possible, upon downward pressure being exerted through cap 25. For a shorter stroke, the plunger is moved downwardly and the clip 30 removed from post 28, and when the desired position of the upper surface of plate 27 is aligned just below a different groove 29, from the one illustrated, for a definition of the length of such shorter stroke, then the clip 30 is seated in that new or different groove, as will be understood. Any number of grooves 29 may be provided on the post 28. The amount of the stroke of the plunger controls the amount of the liquid capable of being discharged from the cylinder 45 and tube 8, as will be explained. A washer-type piston 42, having a central opening adapted to fit removably and snugly on the reduced lower end 41 of the member 8-9, is placed so as to rest thereover upwardly against the peripheral shoulder 41a, when a tensioned snap-wire clip 44 is seated in a groove 43, provided on the outer surface of the plunger-tube 8-9 for that purpose. Clip 44 is of similar design to clip 30, also exerting an inward tension pressure and being removable. I provide a floating cup-shaped cylinder 45, having a pair of diametrically opposed inwardly-extending ears 46 on its rim, for reason to be explained, and a relatively large single intake port 47 in its flat bottom. To assemble the plunger-tube and piston assembly, with the piston within the cylinder, the cylinder is rocked or held at an angle of its rim which is acute to vertical plunger 8-9, using cylinder ears 46 as the axis for that purpose, and then the piston is slipped downwardly into the open cup-cylinder to one side of ears 46, and the cup rim is gradually levelled as the piston enters the cylinder below the said ears. When so

assembled, as illustrated, it will be noted that a vertical lifting of the entire cover and pump assembly, 2-P, will bring the cylinder 45 with it by means of ears 46. The plunger tube and associated parts are so designed that when the adjustable stop means, 27-28-29 and 30, is set for a maximum possible stroke of the plunger-tube, that piston 42 will not then lift cylinder 45, through ears 46, off from cylinder contact with outer container floor 1a. Cylinder intake port, 47, is sealed or closed during down-plunger stroke as a result of its (45) gravity seating on floor 1a, and that sealing is accentuated by a certain amount of liquid compression pressure, formed in 45 during down-piston movement tending to press the cylinder 45 against the upper surface of the outer container floor 1a, exerted through contact with the flat portion of the floor of 45 around 47.

I will now explain the operation of my novel pump-dispenser. Figure 1 illustrates the position of parts before the start of plunger-tube down-stroke operation. Figure 2 illustrates the position after the start and during said plunger down-stroke, when the liquid within the cup-cylinder 45 is being pressed downwardly by the piston 42, and being unable to escape anywhere except upwardly through the tube-plunger 8-9 the liquid is being forced to elevate up that tube and has raised the ball-check 10 and is being discharged from discharge port 23. That discharge of liquid will continue throughout the balance of the down-stroke of the plunger or until the lower portion thereof and the piston reach the position indicated in dotted lines as 48, being the point at which the flange 6a is stopped by the upper surface of the cover 2. Upon release of pressure upon the cap 25 the spring 7 will then raise the plunger assembly, 8-9, 20, 21, 6, and the piston 42 as a part thereof. Upon the start of that raising operation, the suction created by the piston raising off from adjacent the floor of the cup-cylinder, together with the weight of the metallic ball-check valve 10, cause that ball to immediately move down to its valve seat 9a, thereby trapping the liquid within the vertical tube-plunger as that tube-plunger and its piston start the return or rising operation. The continued rising of 8-9 and piston 42 causes sufficient suction to be created within the cup-cylinder 45 for effecting a raising of that cup-cylinder from the floor of the container soon after the start of the return of the plunger-piston. The return of the plunger assembly to the starting point, where the regulator plate 27 is pressed up against the stop clip 30, is caused by tension spring 7, and occurs rapidly before the weight of the cup-cylinder 45 has caused it to fall back down onto container floor 1a, which moment of the return of the pump to the starting point is illustrated in Figure 3. As soon as the cup-cylinder has been raised from the floor, as just explained, the upward suction, just explained, and the weight of the cup-cylinder causing the latter to fall, cause the surrounding liquid L to be sucked into the cup-cylinder, refilling the latter by the time it reaches a sealed condition on floor 1a, ready for another or next downstroke. The interval of time for the cup-cylinder 45 to fall back down onto the floor 1a, after the stop 30 has been reached by plate 27, illustrated in Figure 3, is comparatively very small, depending, of course, upon the viscosity of the liquid within the container being pumped. While I have designed my modification here described and illustrated for use with liquids having

some considerable viscosity resistance, such as melted butter, it may, of course, be satisfactorily used with liquids having a small viscosity resistance. I have found that the ball-check valve 10 may be entirely eliminated, and yet my pump-dispenser satisfactorily used, when rather heavy viscosity liquids are pumped thereby. In the latter instance, the viscosity resistance of the liquid is sufficient to prevent any appreciable falling of the liquid within the tube-plunger, 8-9, and spout, 20, during refilling of the cup-cylinder, as illustrated in Figure 3, without any valve in 9 at all. A very rapid refilling operation, just mentioned, is accomplished as a result of the large intake port 47, making possible quick successive discharge strokes downwardly upon the plunger.

To disassemble my pump-dispenser, as for cleaning purposes, the cover 2, with the entire pump assembly, including the cup-cylinder, are raised vertically off and out of the container 1. Then the cup-cylinder 45 is swung to one side on the ears as a pivot and removed from the piston 42, as previously explained during assembly. Spring clip 44 is removed and the piston taken off the pipe-member, 8-9. Then the spring catch 30 is removed and the plunger 8-9 and plate 27 are lifted upwardly until the lower portion 8 is slipped up and out guide 4. Cap 25 and gasket 26 are then removed. Spout head 21 is removed then, by first lifting the spring yoke 24 on its pivot. Spring cage sleeves 5 and 6, and the spring 7, are then free of any connection. To reassemble my unit, the lower cage 5 is positioned around guide upper projection of 4, the spring 7 placed within cage 5, and then cage 6 is placed over the plunger-tube from the bottom upwardly until it rests against plate 27, and then the plunger, with the cage 6 in such position, is inserted downwardly within the spring, cage 5 and opening in guide 4, until the members 5 and 6 are telescopically associated together against the tension of the spring, and then the opening in collar 40 is placed over post 28, and the catch clip spring 30 placed in a groove 29 after plate 27 is pressed below that clip. Then the piston 42 is replaced and secured by spring clip 44 to the lower part of the plunger, and the cup-cylinder 45 placed over the piston. The cap 45 and spout cap 21 are replaced, and then the entire assembly is placed in the container 1 with the cover portion resting thereon.

It will thus be seen that I have perfected a new pump-dispenser, constructed of the fewest possible number of parts; and yet of sturdy and efficient construction.

Having thus shown and described a preferred embodiment of my invention, it is to be understood that I shall be limited in the scope, spirit and teaching thereof only by the appended claims.

What I claim and desire to secure by Letters Patent is:

1. A pump dispenser comprising, a container having a flat floor and a removable cover, a single vertically operable plunger and discharge tube combined in one member, means for so operably associating the plunger-tube with said cover, adjustable stop means for defining the extent of downward plunger operation, tension means associated with the plunger-tube for normally holding it upwardly, a washer-piston removably and rigidly secured to the lower portion of said plunger-tube, a spout extension from the upper portion of said plunger-tube; and a freely-rockably floating upright open-topped cup-shaped

cylinder associated with said piston and having a flat bottom and a single large intake port formed in its bottom, said port being adapted to be closed upon downstroke operation of the plunger-tube by gravity contact between said cylinder entire bottom and the corresponding surface of the floor of the container, said piston being free to rock during operation and with relation to said piston.

10. 2. A pump dispenser as defined in claim 1, and characterized further by the definition of the cylinder having a diametrically opposed pair of ears inwardly extending from adjacent its top portion, said tension means being in association with said stop means, the adjustable stop means, tension means, piston and cylinder each being removable with relation to each other and the cover, said spout extending from a point a spaced distance below the top of said plunger-tube and above the cover comprising a by-pass, the inner diameter of the plunger-discharge tube being larger than the inner diameter of the spout, and a gravity operable ball check valve within the discharge tube adjacent the spout extension therefrom and being of larger diameter than the internal diameter of the spout and being operable within the discharge tube to be raised, upon and by liquid discharge, to a point within the discharge tube by-pass above the juncture of the spout therewith.
20. 3. A pump-dispenser comprising, a container having a flat floor and a removable cover, a single plunger-tube member mounted for slidable operation through the cover and having a spout extending therefrom above the cover, resilient means associated with the plunger-tube for normally urging it upwardly, adjustable stop means associated with the plunger-tube for defining the extent of downward plunger operation, a washer-type piston removably and rigidly secured to the lower portion of the plunger-tube, and a freely floating and rockable upright-positioned cup-shaped cylinder, rockable with relation to the piston, and having an intake port opening formed in its floor and being loosely associated with said piston, means for effecting such association of the cylinder with the piston, and said cylinder having a fully flat floor portion around said port and with said portion adapted to normally rest on the container flat floor and to thereby effect a closing of said port.

40. 4. A pump-dispenser as defined by claim 3, and characterized further by the definition of the means for effecting said rockable association of the cylinder with the piston as also comprising means for permitting a removal of the cylinder from the piston upon a rocking of the cylinder with relation to the piston.
50. 5. A pump dispenser comprising, a container having a flat floor and a removable cover, a single plunger-tube member slidably extending through the cover and having a spout, resilient means associated with the plunger and cover for normally urging it upwardly, adjustable stop means, including a removable spring clip, for defining maximum plunger operation, a washer-shaped piston rigidly and removably secured to the lower portion of the plunger-tube, and a freely floating and rockable upright cup-cylinder having a diametrically opposed pair of inwardly extending ears adjacent its upper portion and a fully flat floor portion and a single intake port formed in said floor portion, said cup-cylinder being adapted to be closed by said flat portion thereof gravity-resting on the container flat floor, said

piston being removably associated within the cylinder and below said ears, said ears comprising means for effecting said rockable floating of the cylinder with relation to the piston and also for effecting said removable association relationship of the cylinder and piston, and means for so securing said piston to the plunger-tube.

6. A pump dispenser comprising a container having a removable cover and a flat floor, and a pump assembly carried by the cover, said cover having an opening therein, said assembly comprising a guide sleeve secured to the cover and in said opening, a regulator post rigidly secured to the top of the cover at one side and adjacent the opening, a plunger-tube member slidably and snugly operably extending through said sleeve from above the upper side of the cover to therebelow and adjacent the floor of the container and having a reduced portion forming a shoulder at its lower end and a horizontal inner-peripheral ball check valve seat adjacent its upper end and its extreme upper end being removably closed by a cap means, a spout extending from a point below the upper end of the plunger-tube and in a position remote from said post and above said valve seat, a gravity operable ball check valve of larger diameter than the inner diameter of said spout and positioned within the plunger-tube above said valve seat and being adapted to normally rest thereon and to be operably raised above said valve seat by and upon liquid discharge plunger operation, a removable spout head on the outer end of said spout and having a discharge port, spring-yoke means for so securing said head to the spout end, a regulator plate having one end thereof rigidly secured to the outside of the plunger-tube above the cover and the other end thereof formed as a guide means adapted to slidably and snugly encircle and be supported by the post, a pair of telescopically associated spring cage members removably and spacedly enclosing the plunger-tube between the upper surface of the cover and the regulator plate, an outwardly expanding coil tension spring within said cage members, removable spring clip means associated with the post for holding the regulator plate therebelow against the tension of the coil spring, a disc-like piston having an opening adapted to fit snugly and removably over the reduced portion of the plunger-tube and against the said shoulder thereof, removable spring clip means associated with said reduced portion for holding the piston against said shoulder, and a removable floating cup-shaped cylinder associated with said piston and being adapted to normally rest on the floor of the container and having a diametrically opposed pair of ears inwardly extending adjacent the top portion of the cylinder and over said piston and having a single relatively large intake port formed in the floor of the cylinder, said intake port being adapted to be normally closed by a gravity resting of the cylinder upon the floor of the container, said ears comprising means for effecting a holding of the cylinder onto the piston upon vertical lifting of the cover and pump assembly from the container and for disassembling the cylinder and piston by a rocking of the one with relation to the other upon the line of the opposed ears as an axis, the length of the plunger-tube and positioning of the piston thereon with relation to the depth of the container and of the cup-cylinder being such as to permit the piston to be elevated above the floor of the cup-cylinder substantially to a point adjacent the

under side of said ears and so as not to cause the cup-cylinder to be lifted off of the floor of the container when the tension spring holds the plunger in inoperative position.

- 5 7. A pump combination comprising a horizontal surface submerged below the liquid to be pumped, a pipe mounted for a limited vertical down and up movement and extending from above the liquid to a point within the liquid where its extreme downstroke will be in close proximity to the horizontal surface, a disc-like piston rigidly secured to the lower end of said pipe, means for accomplishing vertical return movement of the pipe upon downward movement thereof, a fully floating upright open-topped cup-like cylinder loosely associated with said piston and having an intake port in its floor adapted to be gravity sealed by the cylinder resting on said horizontal surface, said pipe comprising a plunger and discharge tube combined, and means for so associating the cylinder with the piston including a pair of diametrically opposed inwardly extending members carried by the cylinder, said members being adapted for permitting a rocking assembly and disassembly of said cylinder with relation to said piston.
- 10 8. A pump combination comprising a horizontal surface having a vertical pipe operably mounted for limited and adjustable plunger movement therethrough and for returning the pipe to its original position, means for effecting said mounting and returning, a second horizontal surface adapted to be submerged below the liquid to be pumped and positioned a spaced distance below the lower end of the pipe, means for positioning and holding the second surface with relation to the first surface, a washer-shaped piston rigidly and removably secured to the lower end of said pipe, and a fully floating open-topped upright cup-cylinder having a floor and being loosely and removably associated with said piston, an intake port in the cup floor and adapted to be gravity sealed upon a gravity seating of the cup floor with said second horizontal surface, said cup-cylinder being adapted to normally rest on said second surface, said cup-cylinder having a pair of inwardly extending and diametrically opposing ears formed adjacent its upper portion adapted to be normally positioned above said piston, said pipe comprising a plunger and discharge tube combined in one member, said floating cup-cylinder being limited in its floating by its floor on the one hand and by said ears on the other hand each contacting said piston, and said ears comprising means for permitting free rocking of the cup-cylinder with relation to both the ears and the piston, and thereby upon such a rocking with relation to the ears thereby permitting insert or removal of said piston into or out of said cylinder, respectively, and means for so securing the piston to the pipe.

THOMAS L. TITUS.
